UNITED STATES PATENT OFFICE.

WILLIAM M. SMITH, OF BASTROP, LOUISIANA, ASSIGNEE OF ONE-HALF TO LEWLYN
BENTLEY, OF BASTROP, LOUISIANA.

MAIL-BAG CATCHING AND DELIVERING APPARATUS.

1,041,685.

Specification of Letters Patent. Patented Oct. 15, 1912.

Application filed April 4, 1912. Serial No. 688,411.

To all whom it may concern:

Be it known that I, WILLIAM M. SMITH, a citizen of the United States, residing at Bastrop, in the parish of Morehouse and State 5 of Louisiana, have invented certain new and useful Improvements in Mail-Bag Catching and Delivering Apparatus; and I do hereby declare the following to be a full, clear, and exact description of the invention, such as 10 will enable others skilled in the art to which it appertains to make and use the same.

15 It appertains to make and use the same.
This invention relates to mail bag serving apparatus, and it more particularly relates to railroad mail catching and delivering ap-

An object of the invention is to provide means for supporting a mail bag adjacent to a railroad, in the most convenient position and relation to be caught by suitable appliances, carried by a mail car.

A still further object of the invention is to provide an appliance on a mail car, in the most convenient position and relation to be caught by a suitable appliance, near the railroad.

A still further object of the invention is to provide two similar mail bag holders, one of which is carried by a car, the other being supported adjacent to a track on which the car travels, so that the respective mail bags may be exchanged by the two mail bag holders.

A further object is to provide a stationary mail bag supporter, near a railway, the position of which may be adjusted either in a lateral or vertical direction, to suit varying conditions.

A still further object is to provide a traveling and reversible mail bag supporter which is equally applicable to either side of a car or to either side of a car door.

A still further object is to provide a car with a traveling mail bag supporter, and to provide a stationary mail bag supporter adjacent to a track on which the car travels, in such relation that mail bags may be exchanged by the two supporters, regardless of the direction in which the car is traveling.

Further objects and advantages may appear hereinafter and in the claims.

In the accompanying drawings, which form a part of this application, Figure 1 is a side elevation view of a portion of a mail car, having a traveling mail bag supporter thereon, and a track supporting the car and

having a stationary mail bag supporter adjacent thereto. Fig. 2 is a horizontal sectional view of a portion of a car on the line 2-2 of Fig. 1, showing my improved mail serving apparatus applied thereto and to a track on which the car rests, and, Fig. 3 is a vertical sectional view on the line 3-3 of Fig. 1.

Referring to these drawings, in which similar reference characters correspond with similar parts throughout the several views, the body of a mail car is designated by the numeral 5, a door post thereof being designated 6, and to this door post is secured a bracket 7, carrying a vertical pivot 8, on which is rotatably mounted a sleeve 9, which forms a part of a movable bracket 10, the latter having a horizontal arm 10' and a down-turned and horizontally flanged end portion 11, the flange thereof being designated 12.

The horizontal mail bag holders 13, one of which is secured to the flange 12, and at right angles to the arm 10', comprises plates, preferably of metal having their end portions slotted at 14 to a point adjacent to their middle portions, by which they are supported. 80

The supporting medium for the mail bag consists of an elongated member or shank 15, apertured at 16 and provided with similar upper and lower enlargements 17 connected by a neck 18. A strap 19 is engaged by the aperture 16 and embraces the mail bag 20, thereby securing said mail bag in fixed relation to the shank 15. The latter is then inserted in one of the slots 14 so that the upper enlargement 17 rests upon the furcations of the upper bifurcated

the bifurcations of the upper bifurcated holder 13. The other of said bifurcated holders, which we may call the stationary mail bag holder, is supported by an inverted-U-shaped strap of metal 21, which embraces the top part of a post 22, the latter being supported by a pair of stationary brackets 23, fixed adjacent to the track 24 on which the car 5 travels. The post 22 is provided with a vertical slot 25 and an arcuate slot 26, through which bolts 27 and 28 extend respectively. The bolt

27 and 28 extend, respectively. The bolt 27 also extends through the vertical sides of the strap 21 which is adapted to be tightened or clamped against the contiguous sides of the post 22, by means of a nut 27'. By loosening the nut 27', the bolt 27 may be moved upward or downward in the slot 105 110

25, thereby obtaining vertical adjustment of the stationary holder.

The post 22 is pivotally connected at 29 to a prop 30 which is fixed with relation 5 to the brackets 23 and it is obvious, that by loosening the nut 28' the post may be swung on the pivot 29, so that the slot 26 is moved relative to the bolt 28, and the support 13 is moved laterally in a slightly 10 arcuate direction, thereby providing for lateral adjustment of the stationary holder. By tightening the nut 28', the brackets 23 are caused to clamp the contiguous sides of the post 22, thereby holding it in adjusted 15 position. Said adjustment may be found necessary for various conditions, such as variation in the speed of mail trains, curvature of track, etc.; the effect of such conditions being well known by those acquainted 20 with the art. A band 31 may surround the post 22 and strap 21, at any convenient point, for holding said post and strap in the proper relation while being adjusted and clamped together.

25 A keeper 32, having an aperture 33 in the bottom thereof, may be secured to the side of a car, adjacent to the door post 6, by any proper means. Pivotally connected to the down-turned portion 10 is a brace rod 30 34 having a depending lug 35 at its free end, said lug 35 being adapted to fit within the aperture 33, thereby holding the bracket arm 10' at right angles to the doorway and to the side of the car 5. The keeper 32 is 35 provided with a cam surface 36 and with a vertical wall 37 which extends along one side and one end of the keeper, the other side and end thereof being open and unobstructed. A somewhat similar keeper 32' 40 is provided with a wall 37' which is the same as the wall 37 except that it is oppositely disposed with relation to the keeper. In other words, the keepers 32 and 32' might be termed right and left keepers, the outside 45 one being the "right" and the inside one being the "left." By releasing the brace rod 34 from the full-line position shown in Fig. 2, the bracket arm and brace rod may be swung into the dotted-line position, 50 and said brace rod may have its retaining lug 35 enter the aperture 33 of the left hand keeper, whereby the holder 13 will be held within the car, so that danger of contact with external objects along the rail-way is avoided.

The sleeve 9 may be easily lifted from the pivot 8, and transferred to a similar pivot, not shown, on the opposite side of the car or of the door, so that only the one attachment; consisting of the members 9, 10, 10', 12, 13 and 34; is necessary for both sides of the car when transferred as suggested. Obviously, this attachment can be placed on the pivot 8, in the broken line 65 position, and may then be swung in the full-

line position, and in thus applying the attachment, the rod 34 is swung into such position that the retaining lug 35 rests against the cam surface 36, the free end of the rod 34 resting against the wall 37, and by pushing the arm 10' into its full-line position, the lug 35 will be forced over the cam surface and along the wall 37 until it comes into engagement with the aperture 33. In order to assist the cam surface 36 in raising the end of the rod 34, the arm 10' may be raised slightly on the pivot 8, by the operator.

For the purpose of releasing the retaining lug 35 from the aperture 33, I have provided a hand lever 38 having a handle 39 on one end, an upstanding lug 40 on its other end and being pivoted to the car at 41. Obviously, by pressing downward on the handle 39, the lug 40 will come into contact 80 with the retaining lug 35 and lift it out of engagement with the aperture 33, so that the mail bag holder may be swung into the car. Obviously, I may construct the rod 34 of such material and dimensions, that its free end may be raised without raising the other members of the attachment. For instance, it may be constructed of a flat resilient bar of metal, so that it may be swung upward by the action of the lever 38 and by 85 the cam surface 36.

I may construct the several elements of the supporting medium of any proper material; as, for instance; I may construct the shank 15 of metal, leather, rawhide, fiber or 100 composition, while the enlargement thereof and the neck 18 may be of the same material as the shank, or they may be of rubber or of fiber and rubber combined; the principal requisites thereof being comparative lightness and a high degree of toughness.

In operation, considering the car to be moving rightward, the traveling mail bag holder 13 passes over the stationary holder, while the neck 18 of the stationary supporting medium is caught in the slot 14 of the traveling mail bag holder. It will be seen, therefore, that the mail bags may be exchanged, by the apparatus described, while the car moves at a high rate of speed. It 110 will also be seen that, by placing one mail bag and its supporting medium in the left-hand slot of the stationary holder, and the other mail bag and supporting medium in the right-hand slot of the traveling supporter, said mail bags could be exchanged if the car were traveling in the direction opposite to that specified in the foregoing.

It is obvious that I have provided an apparatus which is fully capable of attaining 125 the foregoing objects, and in a thoroughly practical and efficient manner.

I do not limit my invention to the exact details of construction, combination and arrangement of parts, as specified and illus- 130

trated, but my invention may only be limited by a reasonable interpretation of the following claims.

I claim:

- 5 1. In a mail bag serving apparatus, a bracket carrying an upstanding pivot and adapted to be secured to a car door post, a movable bracket having a sleeve adapted to be fitted onto the pivot and to be moved vertically thereon and to be applied thereto and removed therefrom without obstruction, said movable bracket carrying a mail bag holder and having a brace rod pivoted thereto, a detent secured in fixed relation to 15 the first said bracket and adapted to engage the free end of the brace rod for retaining the mail bag holder in operative position and being releasable therefrom so that the mail bag holder may be swung into the car, 20 substantially as shown and specified.
2. In a mail bag serving apparatus, an arm pivotally connected to the side of a mail car door and carrying a mail bag holder, a brace rod pivotally connected to 25 the arm and carrying a retaining lug on its free end, a keeper in fixed relation to the car door and having a cam surface for rais-

ing the retaining lug and guiding it into engagement with the keeper.

3. In a mail bag serving apparatus, an arm pivotally connected to the side of a mail car door and carrying a mail bag holder, a brace rod pivotally connected to the arm and carrying a retaining lug on its free end, a keeper in fixed relation to the car door, having a cam surface for raising the retaining lug for guiding it into engagement with the keeper and means associated with the keeper and the retaining lug, whereby the retaining lug may be lifted out of engagement with the keeper.

4. In a mail bag serving apparatus, a stationary mail bag holder pivotally connected to a stationary prop and having means associated therewith for adjusting the operative position of the holder relative to the prop.

In testimony whereof I have signed my name to this specification in the presence of two subscribing witnesses.

WILLIAM M. SMITH.
